DECORATIVE GRILLE

Robert Porter Hooton, 1511 Marble Ave. NW.,
Albuquerque, N. Mex. 87104

Filed Jan. 14, 1966, Ser. No. 615

Term of patent 14 years

(Cl. D13—1)

Fig. 1

I claim:

The ornamental design for a decorative grille, as shown and described.
